SALES DISPLAY CABINET

Filed June 29, 1925

UNITED STATES PATENT OFFICE.

JENS SORENSEN, OF HARLAN, IOWA.

SALES-DISPLAY CABINET.

Application filed June 29, 1925. Serial No. 40,441.

This invention relates to a sales display cabinet and has for its object, broadly, to provide any required number of compartments for displaying merchandise of various kinds, ready for sale, so that it may be clearly seen and will be protected from dust or other foreign substances, said cabinet to be convenient in use for filling the compartments or for removing the contents therefrom. The invention specifically includes a 10 slideable mounting for the transparent cover-plates for the compartments, and a locking means for said plates, also the use of a single transparent plate and its dust-proof buffers 15 for the front of the cabinet; also the mounting for the swing-doors employed, and the use of upright, segmental housing-plates for the wings of the swing-doors of the compartments. Also a specific object is to provide a 20 sales display cabinet consisting of few and simple parts, so that it may be manufactured practically, conveniently and at a minimum cost.

With the foregoing objects in view and others to be mentioned, the invention presents a novel and useful construction, combination and arrangement of parts as described herein and claimed, and as illustrated in the accompanying drawing, it being understood that changes in form, size, proportion and minor details may be made without departing from the spirit of the invention, said changes being within the scope 30 of the invention as claimed.

In the drawing, Fig. 1 is a view through one of the compartments on line 1—1 of Fig. 4, the door being swung outwardly to its lowermost position. Fig. 2 is a broken away view similar to Fig. 1, the door being 40 swung to a closed position. Fig. 3 is a transverse section on line 3—3 of Fig. 4. Fig. 4 is a broken away, plan view of a compartment and two adjacent compartments. Fig. 5 is an enlarged detail view to show 45 the slideable mounting of the transparent cover-plates for the compartments. Fig. 6 is a broken away plan view, being a sectional detail relating in Fig. 1, to show the mounting of a door-wing and its housing.

Referring now to the drawing, the display cabinet, which preferably is rectangular in plan, is provided with upright, parallel partitions 7 suitably secured to a base or bottom 8 to form a plurality of compartments 9, the upright front wall of the cabinet consisting of a single transparent plate 10, and

the rear of the cabinet consisting of a wall-strip 11 and doors 12 for the several compartments, said rear part of the cabinet having a greater height than its front. The 60 compartments for a cabinet are of uniform length and they may have any desired width, and the width of each door conforms to the width of a compartment of which it may make a closure. 65

Numerals 13 indicate flexible buffer-strips which are provided for the front ends of the partitions, these strips being engaged by the upright transparent wall-plate 10, said strips tending to prevent vibration of said plate 70 and to exclude dust. Numerals 14, best shown in Fig. 5, indicate opposed grooves formed in the partitions for receiving the edge-portions of the transparent cover-plates 15. Numerals 16 indicate frame-strips having a length corresponding to the length of the cabinet, and secured to the upper parts of the partitions are frame-strips 17, the tongues 18 of the partitions 7 to which the strips 17 are secured being of such proportions that the plates 15, preferably constructed of comparatively thick glass, may have 80 free sliding movements in said grooves 14.

Each door 12, at its ends, is provided with a pair of wings 19, each having a flange 20 operating as a stop-member, said wings being of segmental form, and when a door is swung outwardly the wings co-operate with the body of the door to form a container to facilitate removal of the contents of a compartment. 85

Numerals 21 indicate sheet-metal wing housings which form chambers c (Fig. 4.) in which the wings, together with their flanges or stop-members, are adapted to slide when 95 the doors are opened or closed, each housing preferably being of segmental form and provided at one of its rectilinear edges with a flange 22 to be secured to the base 8, its curved edge having a flange 23 adapted to 100 be secured to a partition, and its remaining rectilinear edge having a flange 24 normally disposed in engagement with a wing 19.

While the cabinet may be used for various purposes it is particularly well adapted for 105 containing stock usually sold in groceries or the like, each compartment containing a specific kind of merchandise. Each compartment is provided with a frame 25 for containing a name-plate to identify the particular kind of merchandise in said compartment, each frame being disposed below a 110

cover-plate and secured to the strip 11 at the inner side thereof, above a door. Keepers or latches 26 are employed, each being pivotally mounted upon the outer side of the strip 11 above each door for preventing a movement of a cover 15. The compartments may be conveniently filled by sliding the cover-plates rearwardly after the latches 26 have been moved.

10 It will be appreciated that the housing-plates 21 operate to advantage since they prevent injury to the contents of the compartments which otherwise might be occasioned by the cutting effect of the wings.

15 By referring to Fig. 6 of the drawing it will be seen that each housing-plate is of such form that, while it permits a swinging movement of a door, the flange 24 which engages the wing, prevents entrance to the housing of any finely divided substances when the door is opened or closed.

20 The curved ledge α of each wing-housing operates as a stop to limit the outward swinging movement of a door when said ledge is engaged by the flange 20 of a door-wing. The flanges 22 and 23 which are secured, respectively, to the base 8 and a partition 7 also prevent finely divided substances from entering a wing-housing. Another benefit to be derived by use of the wing-housings is that buckling or bending of the wings will be prevented, and the contents of the compartments will not resist movements of the wings when the doors are moved.

25 30 35 It will be noted that the bottom of each door, when closed, is disposed in line with the upper surface of the base 8 of the cab-

inet, in the vertical plane of the wall-strip 11, said plane being rearwardly of the base 8, said construction providing a recess 27 which permits the door to be swung rearwardly to the position shown in Fig. 1 of the drawing, and which permits the inner surface at its lower edge to practically engage the inner surface of the base 8, and this feature is of advantage since it facilitates removal of the contents of a compartment.

I claim as my invention,—

30 In a display cabinet, the combination with the bottom and side walls of a compartment of the cabinet, said compartment being closed at its front and having a wall-strip at its rear adjacent to its top, and having an opening between its bottom and said wall-strip, of a pair of segmental plates on the inner sides of the side walls, each plate having a longitudinally curved flange engaging one of said side walls and secured to a side and having a flange secured to the bottom of the compartment and a rectilinear flange disposed adjacent to said opening with a part engaging said wall-strip, a hingeably mounted door for said opening, and a pair of segmental wings engaging between the housing-plates and side walls and secured to said door each of said wings having an inwardly extending stop flange at its inner end, and the rectilinear flange of each of said segmental plates engaging the stop flange of the wing to limit the opening of the door.

35 40 45 50 55 60 65 70 75 In testimony whereof, I have affixed my signature.

JENS SORENSEN.
